DESIGN FOR AN ILLUMINATING SUPPORT FOR HAND-HELD LECTURE PAPERS OR SIMILAR ARTICLE

Jean De Jen, Fairfield, Conn.

Application January 28, 1946, Serial No. 126,039

Term of patent 7 years

(Cl. D74—1)

To all whom it may concern:

Be it known that I, Jean De Jen, a citizen of the United States, residing in Fairfield, in the county of Fairfield and State of Connecticut, have invented a new, original, and ornamental Design for an Illuminating Support for Hand-Held Lecture Papers or Similar Article, of which the following is a specification, reference being had to the accompanying drawing, forming part thereof.

Fig. 1 is a perspective view, Fig. 2 is a side view and Fig. 3 is a plan view of an illuminating support for hand-held lecture papers, showing my new design.

I claim:

The ornamental design for an illuminating support for hand-held lecture papers or similar article, substantially as shown.

JEAN DE JEN.
